UNITED STATES PATENT OFFICE.

JOHN C. BARBER, OF CHICAGO, ILLINOIS, ASSIGNOR TO STANDARD CAR TRUCK COMPANY, OF CHICAGO, ILLINOIS, A CORPORATION OF NEW JERSEY.

LATERAL-MOTION DEVICE FOR CAR-TRUCKS.

1,316,554.

Specification of Letters Patent. Patented Sept. 23, 1919.

Application filed March 3, 1919. Serial No. 280,254.

To all whom it may concern:

Be it known that I, JOHN C. BARBER, a citizen of the United States, residing at Chicago, in the county of Cook and State of Illinois, have invented certain new and useful Improvements in Lateral-Motion Devices for Car-Trucks; and I do hereby declare the following to be a full, clear, and exact description of the invention, such as will enable others skilled in the art to which it appertains to make and use the same.

My invention relates to improvements in lateral motion devices for car trucks; and, to this end, the invention consists of the novel devices and combinations of devices hereinafter described and defined in the claims.

In the accompanying drawings, which illustrate the invention, like characters indicate like parts throughout the several views.

Referring to the drawings,

Figure 1 is a side elevation of a car truck having the invention incorporated therein;

Fig. 2 is a view partly in elevation and partly in transverse vertical section taken on the line 2—2 of Fig. 1;

Fig. 3 is a view partly in side elevation and partly in longitudinal vertical section taken on the line 3—3 of Fig. 2;

Fig. 4 is a view principally in transverse vertical section taken on the line 4—4 of Fig. 1;

Fig. 5 is a plan view of one of the combined spring caps and roller bases;

Fig. 6 is a detail view in section taken on the line 6—6 of Fig. 3; and

Fig. 7 is a detail view in section taken on the line 7—7 of Fig. 3.

Each truck side frame includes a top arch bar 8, a bottom arch bar 9, and bolster columns 10 cast integral, one with the other.

As shown, the bottom arch bar 9 is hollow and the top thereof, between the bolster columns 10, is laterally extended on both sides of the truck side frame to afford a base plate 11 having a centrally located annular opening or hole 12 surrounded by an upwardly projecting annular flange or boss 13. The truck side frames are connected by a channel spring plank 14, the end portions thereof rest on the base plates 11. The web or bottom of the spring plank 14 has an opening or hole 15, through which the boss 13 projects, and its top is substantially flush with

the upper face of the web of said spring 55 plank. The parts thus far described are of well known and standard construction.

The numeral 16 indicates a cast bolster, the ends of which extend between the bolster columns 10, with freedom for vertical and lateral movements. Cast with the vertical walls of the bolster 16 at the ends thereof, are stops 17 arranged to engage the outer edges of the bolster columns 10 to limit the lateral movement of said bolster. The bottom of the bolster 16, at the end portions thereof, is upwardly extended between the side walls thereof to afford pockets 18. Cast in the bottom of the bolster 16, within the pockets 18, are roller seats 19 in which rest 70 anti-friction rollers 20 that support said bolster for lateral motion. These anti-friction rollers 20, in turn, rest in seats 21 formed in a combined spring cap and roller base 22.

Interposed between the combined spring 75 cap and roller base 22 and a spring base 23 on the spring plank 14, is a group of four coiled springs 24. Cast with the combined spring cap and roller base 22, is a depending spring-retaining flange 25, which caps the 80 group of springs 24 and holds the upper ends of said springs in assembled position. The spring base 23 is provided at its two edges, which extend transversely of the spring 85 plank 14, with spring-retaining flanges 26 that hold the lower ends of the group of springs 24 in assembled position. This spring base 23 is further provided with an annular opening or bore 27 in axial alignment with the bore 12 in the base plate 11 90 and of the same diameter thereof. It will be noted that the roller base 23 extends between the side flanges of the spring plank 14 and is held thereby against turning movement.

By reference to Fig. 3, it will be noted that the combined spring cap and roller base 22 extends into the pocket 18 and that the anti-friction rollers 20 are held against endwise movement between the side walls of 100 said pocket. It will be also noted that the ends of the roller seats 21 are open and spaced slightly from the side walls of the pocket 18 to permit free lateral movement of the bolster 16 and the escape of dust from 105 said roller seats. The lower portion of the combined spring cap and roller base 25 is expanded and extends under the lower edges

of the side walls of the pocket 18 to receive and cap the upper ends of the group of springs 24.

With the combined spring cap and roller base pocketed in the bolster, as just described, it is impracticable to vertically guide the same in the customary manner, wherein flanges or lugs are formed therewith and arranged to engage the bolster columns as guides. As a novel means for guiding the combined spring cap and roller base 22, I provide, as shown, a pair of vertically disposed telescopically connected members located between the group of springs 24. 10 The lower or outer of said guiding members is indicated by the numeral 28 and affords a column and the upper or inner of said members affords a stem 29 integrally formed with the combined spring cap and roller base 22. The guiding column 28 is held in a fixed upright position, with respect to the roller base 23 and truck side frame, by inserting the lower end portion thereof through the bore 12 in the base plate 11 and seating the same in a socket 30 formed in the upper face of the lower member of the lower arch bar 9. The guiding column 28 also extends through the bore 27 in the spring base 23 and holds the same against 20 lateral movement on the spring plank 16. 25

The guiding stem 29, as previously stated, is integrally formed with the combined roller cap and spring base 25 and extends into the column 28, with freedom for 30 vertical movement, under the action of said combined spring cap and roller base 22. By the use of the above described invention, it is possible to dispense with the bosses customarily formed on spring bases and caps 35 and which extend into the springs to hold the same in position. This means of holding the springs requires considerable labor and time to apply or remove the springs. By the use of my invention, wherein the spring bases and caps are provided with spring capping flanges, it is possible to apply and remove the springs simply by jacking up the bolster sufficiently to permit the springs to be lifted over the flanges 26 on the spring 40 base 23, and which flanges are relatively 45 shallow.

The customary flanges or lugs, heretofore referred to and used as a means for guiding the combined spring cap and roller base 50 from the bolster columns, are objectionable in certain service, for the reason that they would wear the bolster columns out. In my present invention, this objection is overcome by the use of the guiding column. By 55 pocketing the lateral motion device within the bolster, it is possible to use a bolster with wide side flanges, which are now required in certain capacity trucks.

What I claim is:—

65 1. The combination with a truck side

frame, of a bolster, springs and a lateral motion device including a combined spring cap and roller base supporting the bolster from said frame, and telescopically connected guiding members secured, the one to the 70 frame and the other to the combined spring cap and roller base.

2. The combination with a truck side frame, of a bolster, a combined spring cap and roller base, lateral motion devices in 75 interposed between the combined spring cap and roller base and the bolster, springs interposed between said frame and the combined spring cap and roller base, and telescopically connected guiding members se- 80 cured the one to said frame and the other to the combined spring cap and roller base.

3. The combination with a truck side frame, of a bolster, a roller base, a combined spring cap and roller base, anti-friction de- 85 vices interposed between the combined spring cap and roller base and bolster, springs interposed between the roller base and combined spring cap and roller base, and telescopically connected guiding mem- 90 bers secured, the one to the frame and ex- 95 tends through the roller base and the other to the combined spring cap and roller base.

4. The combination with a truck side frame, of a bolster, a roller base, a com- 95 bined spring cap and roller base, anti-friction devices interposed between the combined spring cap and roller base and bolster, springs interposed between the roller base and combined spring cap and roller base, 100 and telescopically connected guiding mem- 105 bers secured, the one to the frame and ex- 110 tends through the roller base and the other to the combined spring cap and roller base, said spring base having flanges cap- 115 ping said spring.

5. The combination with a truck side frame, of a bolster, a roller base, a combined spring cap and roller base, anti-friction de- 110 vices interposed between the combined spring cap and roller base and bolster, springs interposed between the roller base and combined spring cap and roller base, and telescopically connected guiding mem- 115 bers secured, the one to the frame and ex- 120 tends through the roller base and the other to the combined spring cap and roller base, said combined spring cap and roller base having a flange capping said springs.

6. The combination with a truck side frame, of a bolster, a roller base supported from said frame, a combined spring cap and roller base, anti-friction devices interposed between the combined spring cap and roller base and bolster, springs interposed between 125 the roller base and the combined spring cap and roller base, and telescopically connected guiding members secured, the one to said frame and the other to the combined spring cap and roller base, the former of said mem- 130

bers engaging the roller base for holding the same in respect to said frame.

7. The combination with a truck side frame having a socket, of a bolster, a column seated in said socket, a spring base having an opening through which the column projects, a combined spring cap and roller base telescopically connected to the column, springs interposed between the roller base and combined spring cap and roller base, and lateral motion devices interposed between the combined spring cap and roller base and the bolster.

8. The combination with a truck side frame having a socket, of a bolster, a column seated in said socket, a spring base having an opening through which the column projects, a combined spring cap and roller base telescopically connected to the column, springs interposed between the roller base and combined spring cap and roller base, and lateral motion devices interposed between the combined spring cap and roller base and the bolster, said roller base and combined spring cap and roller base having flanges capping said springs.

9. The combination with a truck side frame having a hollow bottom arch bar, said bar having a hole in its top member and a socket in its lower member, of a bolster, a spring base supported from said arch bar and having a hole alined with the hole in the top member of said arch bar, a column extended through said alined holes and seated in said socket, a combined spring cap and roller base having a stem working in said column, springs interposed between the spring base and combined spring cap and roller base, and lateral motion devices interposed between the combined spring cap and roller base and the bolster.

10. The combination with a truck side frame having a hollow bottom arch bar, said bar having a hole in its top member and a socket in its lower member, of a bolster, a spring plank having upturned side flanges supported on said bottom arch bar, a spring

base supported on the spring plank between its side flanges, said spring plank and spring base having holes alined with the hole in the top member of said arch bar, a column extending through said alined holes and seated in said socket, a combined spring cap and roller base having a stem working in said column, springs interposed between the spring base and combined spring cap and roller base, and lateral motion devices interposed between the combined spring cap and roller base and the bolster.

11. The combination with a truck side frame, of a bolster having a pocket, a roller base in said pocket, said bolster and roller base having coöperating roller seats, and anti-friction rollers mounted in said seats and held against endwise movement by the sides of said pocket.

12. The combination with a truck side frame, of a bolster having a pocket, a combined spring cap and roller base extending into said pocket, said bolster and combined spring cap and roller base having coöperating roller seats, the roller seats in the bolster being formed therewith, anti-friction rollers mounted in said seats, and springs interposed between said frame and combined spring cap and roller base.

13. The combination with a truck side frame, of a bolster having a pocket, a combined spring cap and roller base extending into said pocket, said bolster and combined spring cap and roller base having coöperating roller seats, anti-friction rollers mounted in said seats, springs interposed between said frame and combined spring cap and roller base, and telescopically connected guiding members secured, the one to said frame and the other to said combined spring cap and roller base.

In testimony whereof I affix my signature in presence of two witnesses.

JOHN C. BARBER.
